UNITED STATES PATENT OFFICE.

ELMER E. COMSTOCK, OF FRESNO, CALIFORNIA, ASSIGNOR OF ONE-HALF TO JOHN M. HAMBLETON, OF FRESNO, CALIFORNIA.

CRUDE-OIL BURNER.

1,077,123.

Specification of Letters Patent.

Patented Oct. 28, 1913.

Application filed October 3, 1912. Serial No. 723,799.

To all whom it may concern:

Be it known that I, ELMER E. COMSTOCK, a citizen of the United States, residing at Fresno, in the county of Fresno and State of California, have invented a new and useful Crude-Oil Burner, of which the following is a specification.

The present invention appertains to crude oil or hydro-carbon burners, and particularly to those wherein the fuel is atomized and sprayed by steam or other fluid.

It is the object of the present invention to provide a burner of the class designed which shall effect a high degree of combustion of the fuel in a perfect and uniform manner, so as to produce a maximum heating effect with a minimum fuel supply and so as to lessen the amount of soot deposited by the flame.

20 This invention also contemplates the provision of such a burner which shall be comparatively simple, durable and inexpensive in construction, as well as being convenient, economical and efficient in its use.

25 As a further object, the present invention aims to provide novel and improved means for discharging the steam and oil and for adjusting the discharge of each, so that the intensity of the flame can be controlled within practical limits.

With the above and other objects in view, which will appear as the description proceeds, the invention resides in the combination and arrangement of parts and in the

30 details of construction hereinafter described and claimed, it being understood that changes in the precise embodiment of invention herein disclosed can be made within the scope of what is claimed without departing from the spirit of the invention.

The preferred embodiment of the invention has been illustrated in the accompanying drawing, wherein:

Figure 1 is a vertical section of the burner. Fig. 2 is a sectional view on the line 2-2 of Fig. 1, the outer or steam cup being removed. Fig. 3 is a section on the line 3-3 of Fig. 1.

Referring specifically to the drawing, the numeral 1 designates a vertical oil pipe, the lower end of which is connected to a source of oil supply, the oil or other fuel being supplied by gravity or otherwise. A steam pipe

2 enters the oil pipe 1 and passes upward and axially through the oil pipe, the upper

end of the steam pipe being bent angularly as designated by the numeral 3.

The oil pipe 1 is screw threaded externally, and an oil cup 4 has its bottom screw threaded onto the upper end of the oil pipe, and said cup providing an oil chamber 4' within same, and the angular end 3 of the steam pipe passes through the wall or side of the said cup. A disk or partition 5 is screw threaded into the cup 4 and is provided with a central standard or upright 7 carrying a conical cap or hood 6, the standard being connected to the apex of the cap. The disk 5 is provided with a series of openings or apertures 8, in order that the oil or other fuel supplied through the cup may pass upward through the openings 8 in order to flow over the edge of the cup.

A cup 9 surrounds the oil cup 4, the two cups being concentric and providing a steam chamber therebetween with which the steam pipe 2 communicates. The outer or steam cup 9 is provided with an annular outstanding lip or flange 10 at its rim, whereas the oil cup 4 is provided with a similar lip or flange 11 which overhangs the rim or edge of the outer cup. Particular attention is directed to the fact that the lip 10 of the steam cup projects beyond the lip 11 of the fuel cup, the latter lip terminating short of the former lip and the edge of the cap 6. This provides for a sufficient spraying of the fuel as will be apparent.

In order to support the burner within the fire box of a boiler, a base plate 12 has been provided, which has a bowl 12^a and a central opening 12^b. The bottom of the steam cup 9 is convexed and fits or rests within the bowl 12^a and is provided with an extension 13 projecting through the opening 12^b. Any suitable means may be provided for securing the base 12 to the grate or other member in the fire box of a boiler, furnace or the like. It is preferable to connect the steam pipe 2 with the source of steam supply and to connect the oil pipe 1 with a suitable source of oil supply by flexible connections in order that the oil and steam pipes may be adjusted slightly. The bottom of the steam cup 9 is screw threaded on the oil pipe 1, so that both the inner and outer cups are supported by the oil pipe and move therewith.

The outer or steam cup 9 may be adjusted vertically on the oil pipe by means of any

suitable hand lever or wrench 14 engaged to the extension 13, so that by turning the cup 9, the edge or rim thereof shall be spaced more or less from the lip 11 of the inner cup 5 for the purpose of regulating the discharge of steam between the rim of the outer cup and the lip 11 of the inner cup.

The upper face or top of the flange or lip 11 is beveled, or sloped outwardly, the bottom of the flange 11 being provided with a series of radial grooves 15, while the top of the said flange is provided with a complementing series of radial grooves 16. The grooves 15 which are designed for the passage of steam therethrough are comparatively wide, while the grooves 16 which are designed for the passage of oil are comparatively narrow, or approximately half as wide as the grooves 15.

20 If desired, a jam nut 17 may be screw threaded on the oil pipe 1 below the extension 13 of the outer cup in order to clamp a wrench or other implement against the said extension for convenience in manipulating the burner, as will be apparent from the following description.

The bevel of the flange 11 corresponds with the slope of the conical cap 6, the edge or periphery of the cap overhanging both 25 of the lips 10 and 11. The adjoining faces of the lips 10 and 11 are parallel, the upper face of the lip 11 being beveled outwardly, and the lip 10 projecting beyond the lip 11, while the periphery of the cap 6 co-operates 30 with and is cut in a plane parallel with the upper face of the lip 10. The portion of the cap next inside the periphery is parallel with and co-operates with the upper face of the lip 11. Thus, the passage between the 35 adjoining faces of the lips 10 and 11 will be uniform, the passage between the upper face of the lip 11 and the cap 6 will be uniform, and also the passage between the periphery of the cap 6 and the upper face of the lip 10, in order that the most efficient 40 action of the burner will ensue.

In operation, it being understood that the oil and steam pipes are connected to suitable 45 sources of oil and steam supply, or the like, the oil will flow into the cup 4 and when the said cup becomes filled, the oil will overflow and run down the beveled face of the flange 11 toward the flange 10 of the outer cup, and the steam which is supplied to the 50 outer cup through the pipe 2 is discharged outwardly from below the flange 11 so as to take up the overflowing oil and spray same. The steam is thus discharged annularly and the oil is freed annularly above the steam, 55 the flange 11 co-operating with the rim of the outer cup to provide an annular nozzle for the steam and the flange 11 co-operating with the cap 6 to provide an annular nozzle for the oil above the steam nozzle. When 60 the steam cup 9 is adjusted upwardly so

that the rim thereof contacts with the flange 11, and when the cap 6 is adjusted downwardly so as to seat on the beveled face of the flange 11, the steam will be discharged through the grooves 15 and the oil will flow down the grooves 16, so as to provide an annular series of radially projecting flames, which merge together at their outer ends. With the parts adjusted as just defined, the flames will be at a minimum, 70 but sufficient to keep a boiler alive in order to provide sufficient steam for operating the burner. Then, by adjusting the steam cup downwardly by means of a suitable hand lever engaged with the extension 13 of the 75 said cup, the rim of the steam cup is spaced from the flange 11 so as to increase the discharge of steam, which will increase the atomization of the fuel, thereby increasing the combustion and consequent heat. The 80 cap 6 may also be adjusted upwardly when necessary, in order to increase the flow of oil.

It will be noted that the steam pipe in passing through the oil pipe and the chamber within the oil cup will tend to heat the oil prior to its discharge, and further, the steam within the cup 9 surrounding the oil cup and the upper end of the oil pipe will further serve to heat the oil prior to its discharge over the lip 11. The fuel is thus given an initial heat so that the combustion thereof will be made more efficient.

When the base 12 is secured within a fire box of a portable boiler such as in a fire engine, or the like, it is frequently the case that the base will be inclined due to the incline of the boiler or engine when standing on an uneven surface, and as this would produce an uneven flow of the oil over the 100 lip 11, it is essential that the burner may be perpendicular. This is possible, for the reason that the outer cup 9 sets within the bowl 12^a of the base, so that the outer cup may be swung to a perpendicular position on the 105 base by means of the extension 13, with which a wrench or other implement is engageable. The opening 12^b of the base is sufficiently large to permit the extension 13 to move freely therein, as will be understood, and the bowl 12^a may be sufficiently large to permit the free movement of the cup 9 therein, or may snugly embrace the bottom of the cup 9 in order to prevent the cup from swinging relative to the base when 110 the burner is applied in a stationary boiler, furnace or the like.

From the foregoing, taken in connection with the drawing, the advantages and capabilities of this invention will be apparent 115 and it will be noted that the objects aimed at have been carried out in a satisfactory manner, the present burner providing a desirable one for the purposes for which it is designed.

Having thus described the invention, what is claimed as new is—

1. In an oil burner, an outer steam cup, an inner oil cup, an oil pipe attached to the bottom of the oil cup, the steam cup being mounted on the said pipe, and a steam pipe passing through the oil pipe and through the side of the oil cup.
2. In an oil burner, an outer steam cup, an inner oil cup having a lip overhanging the rim of the steam cup, an oil pipe attached to the bottom of the oil cup, the bottom of the steam cup being adjustable on the said pipe, and a steam pipe passing through the oil pipe and through the side of the oil cup.
3. In an oil burner, an outer steam cup, an inner oil cup having an annular lip outstanding from its rim and adapted to seat on the rim of the outer cup, the top and bottom of the lip being provided with series of complementary radial grooves, and a cap seatable on the said lip.
4. In an oil burner, an outer steam cup, an inner oil cup having an annular lip outstanding from its rim and adapted to seat on the rim of the outer cup, the cups being adjustable relative to each other, the top of the said lip being beveled and the top and bottom of said lip being provided with series of complementary radial grooves, and a cap adjustable above the lip.
5. In an oil burner, a base having a bowl provided with a central opening, an outer steam cup having a convexed bottom seating in the bowl and having an extension passing
6. In an oil burner, an outer steam cup, an inner oil cup having a lip overhanging the rim of the steam cup, an oil pipe attached to the bottom of the oil cup, the bottom of the steam cup being adjustable on the oil pipe, and a cap adjustably carried by the oil cup to coöperate with the said lip.
7. In an oil burner, an outer steam cup and an inner oil cup each having an exterior annular lip about its rim, the lip of the oil cup overhanging the rim of the steam cup, the adjoining faces of the lips being parallel, the upper face of the oil cup lip being beveled outwardly, the steam cup lip projecting beyond the oil cup lip, and a conical cap adjustably carried by the oil cup, the periphery of the cap being cut in a plane parallel with and coöoperating with the upper face of the steam cup lip, and the portion next the side of the periphery being parallel with and coöoperating with the upper face of the oil cup lip.

In testimony that I claim the foregoing as my own, I have hereto affixed my signature in the presence of two witnesses.

ELMER E. COMSTOCK.
